UNITED STATES PATENT OFFICE

98,902

DESIGN FOR A COVER FOR SPARE WHEELS AND TIRES OF AUTOMOTIVE VEHICLES

Oscar U. Zerk, Chicago, Ill.

Application April 8, 1935, Serial No. 56,270

Term of patent 7 years

To all whom it may concern:

Be it known that I, Oscar U. Zerk, a citizen of the United States, residing at Chicago, in the county of Cook and State of Illinois, have invented a new, original, and ornamental Design for a Cover for Spare Wheels and Tires of Automotive Vehicles, of which the following is a specification, reference being had to the accompanying drawing, forming a part thereof, in which:

Fig. 1 is a front elevational view of the cover design for spare wheels and tires showing my invention;

Fig. 2 is a perspective view of the embodiment of Fig. 1, taken from the side thereof.

The dominant feature of my design resides in the outwardly flaring rim portion.

I claim:

The ornamental design for a cover for spare wheels and tires of automotive vehicles substantially as shown and described.

In testimony whereof, I hereunto affix my signature this 14 day of March, 1935.

OSCAR U. ZERK.
